UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

FUSE-PLUG.

1,078,458.

Specification of Letters Patent. Patented Nov. 11, 1913.

Application filed December 6, 1911. Serial No. 664,157.

To all whom it may concern:

Be it known that I, HENRY T. PAISTE, a citizen of the United States, residing in Philadelphia, Pennsylvania, have invented 5 certain Improvements in Fuse-Plugs, of which the following is a specification.

This invention relates to fuses of the plug type and has for one of its objects the provision of a structure, which while being 10 similar in its general form to an ordinary fuse plug, shall as a matter of fact be made in two separable parts, one of which carries the fuse proper; it being further desired that the construction shall be such that said 15 latter part, termed the capsule, may be quickly and conveniently replaced when the fuse burns out.

Another object of the invention is to provide a fuse plug consisting of a body portion carrying one of the contacts and the 20 cover, and including a capsule of relatively inexpensive construction carrying the fuse itself; the capsule being removable from the body when necessary on account of the 25 burning out of the fuse.

I further wish to provide a fuse plug having the above noted characteristics with a 30 novel arrangement of passages to permit of the escape of the gas resulting from the blowing of the fuse.

I also desire to provide a two part fuse plug in which those elements of a comparatively costly nature shall be included in one part, while the fuse proper shall be carried 35 upon the relatively inexpensive second part which may be discarded without serious loss when the fuse is burned out, the other portion being repeatedly used with new capsules.

40 These objects and other advantageous ends I secure as hereinafter set forth, reference being had to the accompanying drawings, in which:

Figures 1 and 2, are perspective views of 45 the body and capsule of a fuse constructed according to my invention; Figs. 3 and 4, are respectively vertical sections of the body and capsule shown in Figs. 1 and 2; and Fig. 5, is a plan of the body portion of the 50 fuse structure prior to the mounting thereon of the cap or cover, showing the arrangement of the gas passages.

In the above drawings the body 1 of the fuse is illustrated as consisting of a porce-

lain or other insulating supporting structure of annular form, the opening through which is beveled or outwardly flared at one end. The opposite end of the opening is permanently closed by a transparent sheet 2 of mica or other suitable material held in place by the flange of a metal ring 3, spun or turned over a shoulder of the supporting structure 1 so as to be rigidly held thereto. A metal shell 4 is likewise rigidly mounted in the hole in the structure 1 and for this 65 purpose has a cylindrical portion 5 closely fitting the smaller part of the said hole, and a portion 6 of conical form fitting the flaring part thereof.

The structure 1 is provided with a suitable number of recesses 7 radiating from its central opening or hole at that end adjacent the cover 2 and designed for the reception of lugs or extensions 8 of the part 5 of the shell whereby the latter is rigidly held to the said 75 structure. The outer portion 9 of the shell 4 is provided with threads and is of such a diameter as to screw into a standard fuse plug receptacle.

The fuse proper is carried by a capsule 10 80 of porcelain or other insulating material having two portions 11 and 12 of cylindrical form joined by a part 13 of conical shape. The capsule is hollow for practically its entire length as indicated at 14, and has 85 centrally mounted on that end adjacent the large diameter portion 12 a contact or terminal 15 in the shape of a disk, provided with lugs 16 extending into the hollow 14. One or both of these lugs may be turned 90 over or spread out so as to hold the disk 15 rigidly and permanently in place. Adjacent the open or small diameter end of the capsule I provide in the wall thereof a relatively narrow opening 17 which is flared outwardly 95 from the point where it opens into the recess or hollow 14. At a point on the outer surface of the capsule adjacent the line of junction of the parts 12 and 13 thereof, I provide a small undercut recess 18 for the reception 100 of one end of the fuse 19; the opposite end of this fuse being soldered or otherwise electrically connected to one of the lugs 16 of the disk 15, from whence it extends through the opening 17 and thence over the outer surface of the parts 11 and 13 to the recess 18 into which the end of said fuse is bent or hooked so as to be firmly held therein.

After the fuse has been put in place I preferably fill the openings 17 and 18 with a suitable cement. Under conditions of use the capsule is loosely placed within the shell 5 in the position indicated in dotted lines in Fig. 3, and the threaded portion 9 of said shell is screwed into a socket or receptacle of the ordinary type, until the disk 15 engages the central contact thereof, it being noted that the open end of said capsule projects beyond the extensions or lugs 8. If the electric circuit is otherwise complete, current is now free to flow from the disk 15 to the fuse 19 and thence from the inclined or contact portion of said fuse to the shell 9 and the corresponding shell of the receptacle engaged thereby; it being noted that the act of screwing the shell 9 into the receptacle causes the capsule to be pressed into the 10 conical part of said shell, thereby insuring good electrical contact between that part of the fuse 19 which lies on the inclined surface 13 of the capsule and the inner conical surface of said shell.

20 The condition of the fuse may conveniently be inspected through the transparent cover plate in the well known manner, since the open end of the capsule is immediately adjacent thereto, and when the fuse is blown 25 or broken the capsule, being of relatively inexpensive construction, may be discarded and replaced by another having a perfect fuse. The body of the fuse structure with its relatively expensive pressed shell 4 and 30 cap 3 is thus available for repeated use.

It is noted that I preferably form the opening 17 with its outer end flared in the manner illustrated in Fig. 4, to facilitate the passage through it of the end of the fuse 19, 40 which has previously been soldered to one of the lugs on the disk 15, for the free end of said fuse, after being introduced through the hollow 14, is bent over and threaded through the said opening 17 from the inside thereof. 45 Thereafter the end of the fuse is turned down and hooked in the opening 18 where it is retained even in the absence of cement.

In order to permit escape of the gases formed as a consequence of the "blowing" 50 of the fuse 19 and at the same time render impossible the escape of molten metal or of incandescent gases I form a series of notches 21 in the periphery of the porcelain body 1 and connect these with the radial recesses 7 55 by channels 22 concentric with the center line of the plug. With such arrangement of tortuous passages any gases formed in the interior of the capsule will be so far cooled in passing through the recesses 7, channels 22, and the notches 21 that there is no danger from fire nor any possibility of damage 60 from molten fuse metal.

I claim:

1. The combination in a fuse plug, of a 65 hollow body; a terminal and a structure

having a contact surface on said body; with a fuse capsule of insulating material removably mounted in the body and having an inclined surface formed to co-act with the contact surface on the said body; a 70 terminal on the capsule; and a fuse permanently connected to the terminal and extending over the inclined surface of the capsule in position to engage the contact surface of the body.

2. The combination in a fuse plug of a hollow body; a cap thereon; a threaded shell extending into the body and having an inclined surface; a capsule loosely mounted in the shell and having a terminal with a 80 fuse permanently connected to the terminal and having a portion on the outer surface of the capsule in position to engage the inclined surface of the shell.

3. The combination in a fuse plug of a hollow body having a terminal and a contact surface; a fuse capsule of insulating material loosely mounted in the body and having an inclined surface; a terminal and a conductor carried by the capsule and permanently connected together; said conductor extending over the inclined portion of the capsule in position to engage the contact surface of the body and including a part designed to fuse at a predetermined 95 temperature.

4. As a new article of manufacture, a fuse capsule consisting of a hollow body of insulating material open at one end and having a single exterior contact at the other end; with a conductor including a fuse permanently connected to the end contact and extending through the hollow portion of the capsule, said fuse passing through the wall of the capsule at a point spaced 100 away from the open end and from the outside surface of said capsule to the side portion thereof.

5. As a new article of manufacture, a fuse capsule consisting of a hollow body of insulating material in the form of two cylindrical sections and an inclined section connecting said other sections; a terminal contact at one end of the capsule; with a fuse connected to said contact extending longitudinally through the capsule, through an opening in the side thereof and over a portion of the inclined exterior surface of the capsule.

6. As a new article of manufacture, a fuse capsule consisting of a body of insulating material having an inclined exterior surface and an under-cut recess; a contact mounted on the body; and a fuse connected to said contact extending through the 125 body, over the inclined portion of the exterior surface thereof, and hooked in said under-cut recess.

7. As a new article of manufacture, a fuse capsule consisting of a body of in- 130

- 5 insulating material in the form of an elongated tube closed at one end; a terminal contact at said closed end of the tube; there being an opening through the wall of the tube at the opposite end thereof with a fuse permanently connected to said contact passing therefrom through said opening and extending over the outside surface of the tube in position to serve as a contact.
- 10 8. As a new article of manufacture, a fuse capsule consisting of a body of insulating material in the form of an elongated tube closed at one end; a terminal contact at said closed end of the tube; there being an opening through the wall of the tube at the opposite end thereof formed with its sides outwardly flared; with a fuse connected to said contact, passed through the hollow of the body and the opening in the side wall thereof and then extended over the exterior surface of the body.
- 15 9. As a new article of manufacture a fuse plug body consisting of a hollow supporting structure of insulating material; and an internally threaded shell mounted in said body and projecting to form a terminal; said shell having a portion of its interior surface inclined to its longitudinal axis to form a contact, and engaging a correspond-
- 20 ingly inclined supporting surface within the insulating structure.
10. As a new article of manufacture, a fuse plug body consisting of an outer supporting structure of insulating material provided with a plurality of radiating recesses 35 adjacent one face thereof and a threaded metallic shell having an internal contact portion and a cylindrical portion connected thereto, extending into said supporting structure; said cylindrical portion of the 40 shell being provided with radially extending arms fitting the recesses of said supporting structure.
11. The combination in a fuse plug of a hollow body of insulating material; a metallic shell fitting therein and provided with projecting portions entering recesses in the body; with a fuse capsule removably extending into the shell; the inner end of said capsule being open and projecting into said 45 body beyond the said projecting portions.
- In testimony whereof, I have signed my name to this specification, in the presence of two subscribing witnesses.
- HENRY T. PAISTE.
